TERRAZZO STRIP

Harry L. Fink, New York, N. Y.

Application June 3, 1927, Serial No. 196,230

9 Claims. (Cl. 94—17)

The subject of this invention is a novel and improved dividing or pattern forming strip such as is used for wall and floor structures, for instance, terrazzo floors, where a variegated design is to be exposed on the finished structure. For convenience, therefore, the new strip will be referred to hereinafter as a terrazzo strip, and the advantages of the same will be described in connection with the laying of terrazzo floors.

10 A terrazzo strip, as is well known in the art, is laid during the laying of the floor, and forms an inbuilt part of the completed floor.

One of the objects of the present invention is to provide a terrazzo strip, which may be cheaply 15 formed, as by a stamping operation, for instance out of thin sheet brass; and which, while having portions displaced from the general plane of the strip, for interlocking with the plastic material on one or both sides of the strip, will present 20 these displaced portions otherwise than as tabs or tongues.

Another object is to provide a terrazzo strip of great strength and rigidity and small cost, and at the same time one incorporating portions 25 displaced from the general plane of the strip, for participating in the interlocking feature aforesaid.

Another object is to provide a terrazzo strip as above, and one wherein said displaced portions 30 are nonuniplanar projections, preferably formed by stretching as well as displacing the strip material.

Various other objects and advantages of the invention than those hereinabove mentioned will 35 be specifically pointed out or will be apparent hereinafter in the course of the below detailed description of the forms of the invention shown, in the accompanying drawing, as preferred ones of the various possible embodiments of the invention; it being understood, naturally, that such forms are merely illustrative of some of the many possible combinations and arrangements of parts well calculated to attain the objects of the invention.

40 In said drawing:

Fig. 1 is a perspective view showing a portion of a terrazzo strip incorporating one form of the invention;

Fig. 2 is a similar view showing a portion of a 50 terrazzo strip incorporating another form of the invention.

In the form shown in Fig. 1, the strip, indicated at 6, is illustrated as having a plurality of rounded, upwardly tapering projections 7, 55 formed by pressing out and stretching the strip

material. One projection is on one side of the strip, and the next on the other side of the strip. Opposite the base of each projection 7, there is an edge 8 on the strip, defining an opening 9 through the strip, and through which opening 5 the plastic material may flow, for interlocking the strip to the batches of material on opposite sides thereof.

In the form shown in Fig. 2, the strip, indicated at 6', is illustrated as having hemispherical portions 10 and 11, formed also by pressing out and stretching the strip material. The projections 10 and 11 in the present case are of the same size and shape and project oppositely in regular alternation; the projections 10 being on 10 the side of the strip facing the observer, and establishing on the opposite side of the strip recesses for the reception of the plastic material, and the projections 11 being on the side of the strip away from the observer, thus establishing 15 their recesses on the side of the strip facing the observer. The latter recesses are indicated at 12.

Inasmuch as many changes could be made in the above constructions, and many apparently widely different embodiments of the invention 20 could be made without departing from the scope thereof, it is intended that all matter contained in the above description or shown in the accompanying drawing shall be interpreted as illustrative and not in a limiting sense.

It is also to be understood that the language contained in the following claims is intended to cover all the generic and specific features of the invention herein described and all statements of the scope of the invention which, as a matter of 25 language, might be said to fall therebetween.

I claim:

1. A strip for the purpose described having 30 pocket forming portions projecting from the sides thereof with the edges of the pockets all in a single plane at right angles to the strip and spaced from one of the longitudinal edges of the strip.

2. A strip for the purpose described having 40 segmento-conoidal portions struck out from the body of the strip and each having an arcuate edge portion free from the body of the strip whereby said portions form pockets open at one end, said arcuate edge portions all lying in a common plane at right angles to the body of the strip and spaced from the edge towards which the pockets face.

3. A strip for the purpose described, having 50 an uninterrupted straight longitudinal upper edge and having segmento-conoidal portions 55

struck out from the body of the strip forming in each instance a depression at the side and extending transversely of the strip, one end and the body of each depression being continuous with the strip, and the other end of each depression separate from the strip, the edges constituting said opposite ends of each depression being all, and each in its entirety, in a plane parallel to and spaced from the said longitudinal edge of the strip, and the first named end of the depression being adjacent the other longitudinal edge of the strip.

4. A strip for the purpose described, having an uninterrupted straight longitudinal upper edge and having segmento-conoidal portions struck out from the body of the strip forming in each instance a depression at the side and extending transversely of the strip, one end and the body of each depression being continuous with the strip, and the other end of each depression separate from the strip, the edges constituting said opposite ends of each depression being all, and each in its entirety, in a plane parallel to and spaced from the said longitudinal edge of the strip, and the first named end of the depression being adjacent the other longitudinal edge of the strip, one of such depressions being located at one side of the strip, and another of such depressions being located at the opposite side of the strip.

5. A strip for the purpose described, having an uninterrupted straight longitudinal upper edge and having segmento-conoidal portions struck out from the body of the strip forming in such instance a depression at the side and extending transversely of the strip, one end and the body of each depression being continuous with the strip, and the other end of each depression separate from the strip, the edges constituting said opposite ends of each depression being all, and each in its entirety, in a plane parallel to and spaced from the said longitudinal edge of the strip, and the first named end of the depression being adjacent the other longitudinal edge of the strip, said depressions being spaced longitudinally of the strip and extending alternately at opposite sides thereof.

6. A dividing strip having projecting laterally therefrom a plurality of scoop-shaped portions spaced longitudinally along the strip, each of said scoop-shaped portions having a mouth directed toward and spaced from a longitudinal edge of the strip, the mouth being defined by a free edge spaced laterally from the plane of the strip, substantially all of the remaining periphery of the scoop-shaped portion being attached to the strip.

7. A dividing strip having projecting from the opposite sides thereof a plurality of scoop-shaped portions spaced longitudinally along the strip, each of said scoop-shaped portions having a mouth directed toward and spaced from a longitudinal edge of the strip, the mouth being defined by a free edge spaced laterally from the plane of the strip, substantially all of the remaining periphery of the scoop-shaped portion being attached to the strip.

8. A dividing strip having projecting laterally therefrom a plurality of scoop-shaped portions spaced longitudinally along the strip, each of said scoop-shaped portions having a mouth directed toward and spaced from the bottom longitudinal edge of the strip, the mouth being defined by a free edge spaced laterally from the plane of the strip, substantially all of the remaining periphery of the scoop-shaped portion being attached to the strip.

9. A terrazzo strip comprising a strip of metal having a straight uninterrupted upper edge, the metal of the strip being cut at successive locations and portions of the metal adjacent to the cuts being stretched laterally into scoop-shaped portions, each of said scoop-shaped portions having a mouth defined by a free edge which curves laterally away from the plane of the strip and then back to the plane of the strip, substantially all of the remaining periphery of the scoop-shaped portion being integral with the strip.
